UNITED STATES PATENT OFFICE.

CHARLES S. LUDWIG, OF TRENTON, NEW JERSEY.

JELLY-STRAINER.

1,353,056.

Specification of Letters Patent. Patented Sept. 14, 1920.

Application filed March 20, 1920. Serial No. 367,364.

To all whom it may concern:

Be it known that I, CHARLES S. LUDWIG, a citizen of the United States, residing at Trenton, in the county of Mercer and State 5 of New Jersey, have invented new and useful Improvements in Jelly-Strainers, of which the following is a specification.

This invention relates to improvements in jelly strainers and fruit presses, and has 10 for an object the provision of a device, by means of which the juices may be squeezed from either fresh or cooked fruits, without staining or burning the hands.

Another object of the invention is the 15 provision of a device of this character, by means of which the maximum amount of juice may be obtained from the fruit and the operation performed with a minimum amount of time and labor.

20 Other objects and advantages of the invention will appear as the following description is read in connection with the accompanying drawings,

In the drawings:—

25 Figure 1 is a side elevation showing the invention in position for use.

Fig. 2 is a plan view of the same.

Fig. 3 is a sectional view on the line 3—3 of Fig. 1.

30 Fig. 4 is a vertical section on the line 4—4 of Fig. 1.

Fig. 5 is an enlarged view showing the connection between the squeezing members and the adjustable positioning nuts.

35 Fig. 6 is a detail view of one of the squeezing members equipped with a detachable plate for use in connection with the small fruits.

Fig. 7 is a transverse sectional view of the 40 same.

Referring in detail to the drawings, wherein like characters of reference denote corresponding parts, the invention comprises a base 10 which may be of suitable 45 size and shape. This base is provided with a threaded socket 11 at one end thereof, which is adapted to immovably receive the threaded end of a standard 12. This standard is hollow and receives within its upper 50 end one end of an angular arm 13, which is held stationary with respect to the standards by means of a set screw 14. The opposite end of the arm 13 is connected to a hori-

zontally arranged ring 15 which is designed to hang as a support for a container in the 55 form of a cloth bag 16.

The bag 16 is open at its top and is secured to a ring 17 of slightly greater diameter than the ring 14, so that when the bag is passed through the last mentioned ring, it 60 will be held suspended with the ring 17 resting upon the ring 15.

Mounted for sliding movement upon the standard 12 is a block 18, the latter being held in adjusted position upon the standard 65 by means of a set screw 19. Pivotedly secured to the block 18 is a pair of squeezing members 20. These members are formed of substantially parallel side bars 21, which are connected by transverse bars 22 and form a 70 grate like arrangement having projecting from one end an arm 23, which is pivotally connected to the nut 18, while projecting from the opposite ends of the grate like squeezing members are handles 24. After 75 the fruit has been placed within the bag 16 and the pivoted ends of the squeezing members adjusted to the proper height upon the standard 12, a squeezing action may be applied to the fruit within the bag by pressing the handles of the squeezing members 80 toward one another as will be apparent. The bag may be revolved or turned within the ring 15 and the squeezing action applied to its contents a number of times until all 85 of the juices have been extracted from the fruits. The base 10 is of sufficient size to act as a support for a receptacle 24 to receive the juices.

For use in connection with small fruits 90 such as berries, cherries and the like, there is provided a perforated plate 25, which is adapted to be removably secured along the inner faces of the squeezing members 20 as illustrated in Figs. 6 and 7 of the drawings. 95 Any desired means may be employed for holding the plate 25 in position.

The invention is susceptible of various 100 changes in its form, proportion and minor details of construction, and the right is here reserved to make such changes as properly fall within the scope of the appended claims.

Having thus described my invention what I claim as new is:—

1. A device of the class described com-

prising a standard, a bag suspended therefrom, a block slidably and adjustably mounted on said standard, and a pair of squeezing members pivotally mounted on the block.

2. A device of the class described comprising a base, a standard secured thereto, a

laterally extending horizontally disposed ring supported by said standard, a bag removably secured to the ring and a pair of 10 squeezing members pivotally and adjustably mounted on said standard.

In testimony whereof I affix my signature.

CHARLES S. LUDWIG.
